(57) **CLAIM**

The ornamental design for a lingerie wrap, as shown and described.

DESCRIPTION

FIG. 1 illustrates a front left-side perspective view of a lingerie wrap;

FIG. 2 illustrates a front view thereof;

FIG. 3 illustrates a rear view thereof;

FIG. 4 illustrates a left-side view thereof;

FIG. 5 illustrates a right-side view thereof;

FIG. 6 illustrates a top view thereof;

FIG. 7 illustrates a bottom view thereof; and,

FIG. 8 illustrates a front right-side perspective view showing the lingerie wrap worn by a wearer.

In FIGS. 1-3 and 8, the short-dash broken lines illustrating a grid pattern on the fabric of the lingerie wrap represents portions of the design which form no part of the claimed design. Furthermore, in FIGS. 1-3 and 8, the longer dash broken lines illustrating the filigree and floral patterns on the fabric of the lingerie wrap represents portions of the design which form no part of the claimed design. Furthermore, in FIGS. 1-3, the short dash lines on the clasp of the lingerie wrap represents stitching that does not form part of the claimed design. Furthermore, in FIG. 8, the long dash lines illustrating a person wearing the lingerie wrap represents environment of the claim which forms no part of the claimed design.

1 Claim, 8 Drawing Sheets
